UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

SUITCASE.

1,131,443.

Specification of Letters Patent.

Patented Mar. 9, 1915.

Application filed March 10, 1913. Serial No. 753,193.

To all whom it may concern:

Be it known that I, HUGO TUECKMANTEL, a citizen of the United States, residing at Irvington, in the county of Essex and State of New Jersey, have invented certain new and useful Improvements in Suitcases; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to improvements in suit-cases, and receptacles of a similar character; and this invention relates, more particularly, to a novel construction of metal frame for the body of a suit-case or like receptacle, and a novel means for pivotally connecting the cover-frame thereof to the frame of the body of the receptacle.

20 The present invention has for its principal object to provide a novel and simply constructed metal frame for the body of a suit-case, or other suitable receptacle, having an overlapping cover, with a view of providing a positive means for readily securing the marginal edge-portions of the sides of the body of the receptacle to the metal frame; and, also to provide a surrounding off-set, commonly termed in the art as the "bevel," with which the surrounding edge-portions of the cover can be brought into perfect registration, when closed, so as to provide a neat overlapping relation of the cover with the body of the receptacle.

25 The invention has for its further object to provide a simple and effective, as well as a strong means of construction for hinging or pivotally connecting the cover with the body of the receptacle, to obviate the danger of breaking the cover or body-portions with the constant opening and closing of the cover.

30 The invention has for its further object to provide a metal frame comprising such other new and improved constructions and arrangements of parts which is more readily applicable to suit cases or other receptacles,

the bodies and covers of which are made of fiber, paper, leather, or straw-fabric, hereinafter fully set forth.

55

Other objects of the present invention not at this time more particularly enumerated will be clearly evident from the following detailed description of the said invention.

With the various objects of the said invention in view, the invention consists, primarily, in the novel suit-case or receptacle-construction hereinafter set forth; and, the invention consists, furthermore, in the novel arrangements and combinations of the various devices and parts, as well as in the details of the construction of the said parts, all of which will be more fully described in the following specification, and then finally embodied in the clauses of the claim which are appended to and which form an essential part of this specification.

60 The invention is clearly illustrated in the accompanying drawings, in which:—

Figure 1 is a top-edge view of a suit-case or receptacle, made according to and embodying the principles of the present invention, the cover being shown in its closed relation with the body and its "bevel" of the suit-case or receptacle. Fig. 2 is a plan view of the suit-case or receptacle, the body and cover being represented in their opened relation. Fig. 3 is a detail vertical section, on an enlarged scale, said section being taken on line 3—3 in said Fig. 1; and Fig. 4 is a detail vertical section, also on an enlarged scale, said section being taken on line 4—4 in said Fig. 2, looking in the direction of the arrow *x*. Fig. 5 is a transverse vertical section, taken on line 5—5 in said Fig. 4, looking in the direction of the arrow *y*; and Fig. 6 is a similar section, taken on line 6—6 in said Fig. 4, also looking in the direction of the arrow *y*. Fig. 7 is a detail perspective view of one of the corner-portions of the metal frame with which the body of the suit-case or receptacle is provided; Fig. 8 is a top-edge view of the parts represented in said Fig. 7; and Fig. 9 is a face view of a portion of the metal body-frame, before being transformed into the angular corner-portion represented in said Figs. 7 and 8.

100 Similar characters of reference are em-

ployed in the said above described views, to indicate corresponding parts.

Referring now to the said drawings, the reference-character 1 indicates the body of the suit-case, or other suitable receptacle, and 2 indicates the cover of the same, both of which may be made of fiber, paper, leather, straw or any other fabric. The metal body-frame which is made of sheet-metal, and which is secured to the marginal edge-portions of the sides of the said body 1 in the manner to be presently set forth, is preferably made in two sections, one of which, as 3, is connected with the front and 15 the two end members of the said body, and the other member 4 is connected with the back or rear member of said body. The said frame-section 3 comprises an inner body-portion 5 which is adapted to be arranged 20 against the inner face-portions of the said front and end-members of the body 1, at the upper marginal portions of said front and end-members, the upper edge of the said body-portion 5 of the strip of metal 25 being curved outwardly and downwardly, as at 6, so as to form a smooth and preferably rounded upper edge or connecting member, substantially as shown in the several figures of the drawings. Extending 30 downwardly from the said upper rounded edge 6 of the strip of metal is an outer portion or member 7 of less depth than the depth of the body-portion 5, said portion or member 7 being located upon the outer faces 35 of the upper surface-portions of the front and end-members of the body 1, and provides with said body-portion 5 of the strip of metal, a recess or receiving part, as 8, in which the upper edge-portions of the front 40 and end-members of the body 1 are arranged and are clamped therein in the manner to be presently described. Upon the lower marginal edge-portion of the said member 7 is an outwardly extending, and downwardly 45 and inwardly curved bead-like member, 9, terminating at a point beneath the said recess or receiving part 8 in a slightly upwardly projecting or angularly arranged biting or clamping edge 10, the bead-like member 9 providing a seat upon the outer portions of the metal body-frame with which the frame of the cover 2, to be hereinafter more fully described is adapted to be brought 50 into perfect registration and with which seat the frame of the cover co-operates to provide a perfect closure of the cover with the body of the receptacle.

In Figs. 1 and 2 of the drawings, it will be seen, that the frame-section 3 is bent at 60 the corners 11 and 12 in such a manner so as to provide open spaces upon the outer portions of the frame-section at said corners, the member 7 and the bead-like member 9 at said points being suitably cut away, 65 to permit of the proper bending and angu-

lar arrangement of the frame-section at these points. It will be understood, however, from an inspection of Figs. 7, 8 and 9, that at the proper points the main body-portion of the strip of metal may be cut 70 away, as at 13, the bead-like member 9 being also suitably cut away, as at 14, see Fig. 9, which enables the frame-section to be bent, as indicated in said Figs. 7 and 8, so as to provide the frame upon its outer portions 75 with solid or unbroken corners, as will be clearly evident.

Referring now to Figs. 2 and 3 of the drawings, it will be seen, that at their free end-portions, the side-members of the frame-section 3 are provided with laterally and inwardly projecting ears or lugs, as 15, bent at right angles from the end-portions of the main body-strip 5, said ears or lugs 15 being suitably perforated and having secured thereto by means of rivets 16, the previously-mentioned rear or back-strip 4. This rear or back-strip 4 comprises an inner body-portion 17 which is adapted to be arranged 85 against the inner face-portion of the back 90 or rear member of the body 1 of the receptacle, at the upper marginal portion of said back or rear member, the upper edge of the said body-portion 17 being curved outwardly and downwardly, as at 18, so as to 95 form a smooth and rounded upper edge. Extending downwardly from the said upper rounded edge 18 is a downwardly extending portion or member 19 which is located upon the outer face of the upper portion of the 100 said back or rear member of the body 1 of the receptacle, and provides with the said body-portion 17 a suitable recess or receiving part, as 20, in which the upper edge-portion of the back or rear member of the 105 body 1 is arranged and clamped. At suitable intervals, along the entire length of the said downwardly extending portion or member 19, and connected with the lower marginal edge-portion of said member 19, 110 are a series of curled pintle-receiving ears or members 21, as illustrated more particularly in Figs. 4 and 5 of the drawings.

Suitably inclosing the marginal edge-portions of the front, ends, and the rear or 115 back-member of the cover 2 of the suitcase or other receptacle is a cover-frame-section, as 22, said frame-section, in this case, consisting of a number of sectional members, as 23, which are bent so as to provide 120 channel-members which are slipped over the marginal edges of the front, ends, and the rear or back member of the cover, as will be evident from an inspection of the several figures of the drawings, and are secured together at their respective meeting ends, so as to provide the cover-frame-section, by means of suitable corner-pieces 24 and rivets 25, the frame-section which is thus produced being at the same time secured to 130

the said front, ends, and the back or rear member of the cover 2 by means of the said rivets 25. That the said cover 2 may be hinged to the body 1 of the suit-case or other receptacle, there is secured upon the rear or back section of the said cover-frame-section, by means of rivets 26, or in any other suitable manner, a strip of metal, as 27, which is provided upon its upper marginal edge-portions, and at suitable intervals, so as to be fitted between the previously-mentioned pintle-receiving ears or members 21, with upwardly extending curled pintle-receiving ears or members 28. These ears 28 are pivotally connected with the ears 21 by means of a long pintle-rod 29, in the manner clearly represented in Figs. 2, 4, 5 and 6 of the drawings.

The simplicity of the construction of the several parts of the two metal frame-sections and the manner of easily and quickly securing them in their operative positions upon the body and cover of the receptacle, as well as the manner in which the cover is thus caused to perfectly register and close with the body of the receptacle is clearly obvious from the foregoing description of the present invention and from an inspection of the several figures of the drawings.

I am also fully aware that changes may be made in the general arrangements and combinations of the various devices and parts, as well as in the details of the construction of the frame-sections, without departing from the scope of the present invention as set forth in the foregoing specification and as defined in the clauses of the claim which are appended thereto. Hence, I do not limit my present invention to the exact arrangements and combinations of the devices and parts as described in the said specification, nor do I confine myself to the exact details of the construction of the said parts, as illustrated in the accompanying drawings.

I claim:—

1. In a receptacle, the combination with the body thereof and a cover therefor, of a rigid frame to give a bevel to the edge of said body, said frame comprising a pair of vertically disposed portions and an upper connecting member, arranged to provide a receiving part in which the upper portions of the body are arranged, an off-set extending outwardly from one of said vertically disposed portions and located upon the outer face-portions of said body, said off-set forming a seat, and a clamping edge-portion extending inwardly from said off-set in biting engagement with the said outer face-portions of said body, said cover registering with said frame and coöperating with said seat to provide a perfect closure of said cover with said body.

2. In a receptacle, the combination with

the body thereof, of a rigid frame to give a bevel to the edge of said body, said frame comprising a pair of vertically disposed portions and an upper connecting member, arranged to provide a receiving part in 70 which the upper portions of the body are arranged, an off-set extending outwardly from one of said vertically disposed portions and located upon the outer face-portions of said body, said off-set forming a 75 seat, and a clamping edge-portion extending inwardly from said off-set in biting engagement with the said outer face-portions of said body, combined with a cover, a channel shaped frame arranged over the 80 marginal edge-portions of said cover, and a means of pivotal connection between said channel-shaped frame and the frame of said body, said channel-shaped frame of the cover registering with the frame of said 85 body and coöperating with said seat to provide a perfect closure of said cover with said body.

3. In a receptacle, the combination with the body thereof, and a cover therefor, of a 90 rigid frame to give a bevel to the edge of said body, said frame comprising an inner body-portion adapted to be arranged upon the inner face-portions of said body at the upper marginal edge-portions thereof, said 95 inner body-portion being formed upon its upper marginal edge-portion with a curved outwardly and downwardly extending connecting member, an outer member extending downwardly from said connecting member, 100 said outer member being of less depth than the depth of said inner body-portion and forming with said inner body-portion a receiving part in which the upper portions of the body are arranged, and an off-set forming 105 a seat extending outwardly from said vertically disposed outer member and located upon the outer face-portions of said body, and at a point below the said connecting member, said cover registering with said 110 frame and coöperating with said seat to provide a perfect closure of said cover with said body.

4. In a receptacle, the combination with the body thereof, and a cover therefor, of a 115 rigid frame to give a bevel to the edge of said body, said frame comprising an inner body-portion adapted to be arranged upon the inner face-portions of said body at the upper marginal edge-portions thereof, said 120 inner body-portion being formed upon its upper marginal edge-portion with a curved outwardly and downwardly extending connecting member, an outer member extending downwardly from said connecting member, 125 said outer member being of less depth than the depth of said inner body-portion and forming with said inner body-portion a receiving part in which the upper portions of the body are arranged, an off-set forming a 130

4

seat extending outwardly from said vertically disposed outer member and located upon the outer face-portions of said body, and at a point below said connecting member, and a clamping edge-portion extending inwardly from said off-set in biting engagement with the said outer face-portions of said body, said cover registering with said frame and coöperating with said seat to provide a perfect closure of said cover with said body.

5. In a receptacle, the combination with the body thereof, of a rigid frame to give a bevel to the edge of said body, said frame comprising an inner body-portion adapted to be arranged upon the inner face-portions of said body at the upper marginal edge-portions thereof, said inner body-portion being formed upon its upper marginal edge-portion with a curved outwardly and downwardly extending connecting member, an outer member extending downwardly from said connecting member, said outer member being of less depth than the depth of said 25 inner body-portion and forming with said inner body-portion a receiving part in which the upper portions of the body are arranged, an off-set forming a seat extending outwardly from said vertically disposed outer member and located upon the outer face-portions of said body, and at a point below said connecting member, combined with a cover, a channel-shaped frame arranged over the marginal edge-portions of said 30 cover, and a means of pivotal connection between said channel-shaped frame and the frame of said body, said channel-shaped frame of the cover registering with the frame of said body and coöperating with said seat to provide a perfect closure of said cover with said body.

6. In a receptacle, the combination with the body thereof, of a rigid frame to give a bevel to the edge of said body, said frame comprising an inner body-portion adapted to be arranged upon the inner face-portions of said body at the upper marginal edge-portions thereof, said inner body-portion being formed upon its upper marginal edge-portion with a curved outwardly and downwardly extending connecting member, an outer member extending downwardly from said connecting member, said outer member being of less depth than the depth of said 55 inner body-portion and forming with said inner body-portion a receiving part in which the upper portions of the body are arranged, an off-set forming a seat extending outwardly from said vertically disposed outer member and located upon the outer face-portions of said body, and at a point below said connecting member, and a clamping edge-portion extending inwardly from said off-set in biting engagement with the said 60 outer face-portions of said body, combined 65 outer face-portions of said body, combined

with a cover, a channel-shaped frame arranged over the marginal edge-portions of said cover, and a means of pivotal connection between said channel-shaped frame and the frame of said body, said channel-shaped frame of the cover registering with the frame of said body and coöperating with said seat to provide a perfect closure of said cover with said body.

7. In a receptacle, the combination with the body thereof and a cover therefor, of a rigid frame to give a bevel to the edge of said body, said frame comprising a pair of vertically disposed portions and an upper connecting member, arranged to provide a receiving part in which the upper portions of the body are arranged, one of said vertically disposed portions being provided at pre-determined points with cut away parts, and an off-set forming a seat extending outwardly from one of said vertically disposed portions and located upon the outer face-portions of said body, said cover registering with said frame and coöperating with said seat to provide a perfect closure of said 90 cover with said body.

8. In a receptacle, the combination with the body thereof and a cover therefor, of a rigid frame to give a bevel to the edge of said body, said frame comprising a pair of vertically disposed portions and an upper connecting member, arranged to provide a receiving part in which the upper portions of the body are arranged, one of said vertically disposed portions being provided at 95 pre-determined points with cut away parts, an off-set forming a seat extending outwardly from one of said vertically disposed portions and located upon the outer face-portions of said body, and a clamping edge-portion extending inwardly from said off-set in biting engagement with the said outer face-portions of said body, said cover registering with said frame and coöperating with said seat to provide a perfect closure of said 100 cover with said body.

9. In a receptacle, the combination with the body thereof, of a rigid frame to give a bevel to the edge of said body, said frame comprising a pair of vertically disposed portions and an upper connecting member, arranged to provide a receiving part in which the upper portions of the body are arranged, one of said vertically disposed portions being provided at pre-determined points with 115 cut away parts, an off-set forming a seat extending outwardly from one of said vertically disposed portions and located upon the outer face-portions of said body, combined with a cover, a channel-shaped frame arranged over the marginal edge-portions of said cover, and a means of pivotal connection between said channel-shaped frame and the frame of said body said channel-shaped frame of the cover registering with the 120 125 130

frame of said body and coöperating with said seat to provide a perfect closure of said cover with said body.

10. In a receptacle, the combination with the body thereof, of a rigid frame to give a bevel to the edge of said body, said frame comprising a pair of vertically disposed portions and an upper connecting member, arranged to provide a receiving part in which the upper portions of the body are arranged, one of said vertically disposed portions being provided at pre-determined points with cut away parts, an off-set forming a seat extending outwardly from one of said vertically disposed portions and located upon the outer face-portions of said body, and a clamping edge-portion extending inwardly from said off-set in biting engagement with the said outer face-portions of said body,
- 15 20 25 30 35 40 45 50 55 60 65
- combined with a cover, a channel-shaped frame arranged over the marginal edge-portions of said cover, and a means of pivotal connection between said channel-shaped frame and the frame of said body said channel-shaped frame of the cover registering with the frame of said body and coöperating with said seat to provide a perfect closure of said cover with said body.

11. In a receptacle, the combination with

- the body thereof and a cover therefor, of a rigid frame to give a bevel to the edge of said body, said frame comprising an inner body-portion adapted to be arranged upon the inner face-portions of said body at the upper marginal edge-portions thereof, said inner body-portion being formed upon its upper marginal edge-portion with a curved outwardly and downwardly extending connecting member, and an outer member extending downwardly from said connecting member, said outer member being of less depth than the depth of said inner body-portion and forming with said inner body-portion a receiving part in which the upper portions of the body are arranged, said outer and downwardly extending member being provided at predetermined points with open parts, and an off-set forming a seat extending outwardly from said outer and downwardly extending member and located upon the outer face-portions of said body, said cover registering with said frame and coöperating with said seat to provide a perfect closure of said cover with said body.

12. In a receptacle, the combination with the body thereof and a cover therefor, of a rigid frame to give a bevel to the edge of said body, said frame comprising an inner body-portion adapted to be arranged upon the inner face-portions of said body at the upper marginal edge-portions thereof, said inner body-portion being formed upon its upper marginal edge-portion with a curved outwardly and downwardly extending connecting member, and an outer member ex-

tending downwardly from said connecting member, said outer member being of less depth than the depth of said inner body-portion and forming with said inner body-portion a receiving part in which the upper portions of the body are arranged, said outer and downwardly extending member being provided at pre-determined points with open parts, an off-set forming a seat extending outwardly from said outer and downwardly extending member and located upon the outer face-portions of said body, and a clamping edge-portion extending inwardly from said off-set in biting engagement with the said outer face-portions of said body, said cover registering with said frame and coöperating with said seat to provide a perfect closure of said cover with said body.

13. In a receptacle, the combination with the body thereof, of a rigid frame to give a bevel to the edge of said body, said frame comprising an inner body-portion adapted to be arranged upon the inner face-portions of said body at the upper marginal edge-portions thereof, said inner body-portion being formed upon its upper marginal edge-portion with a curved outwardly and downwardly extending connecting member, and an outer member extending downwardly from said connecting member, said outer member being of less depth than the depth of said inner body-portion and forming with said inner body-portion a receiving part in which the upper portions of the body are arranged, said outer and downwardly extending member being provided at pre-determined points with open parts, an off-set forming a seat extending outwardly from said outer and downwardly extending member and located upon the outer face-portions of said body, combined with a cover, a channel-shaped frame arranged over the marginal edge portions of said cover, and a means of pivotal connection between said channel-shaped frame and the frame of said body, said channel-shaped frame of the cover registering with the frame of said body and coöperating with said seat to provide a perfect closure of said cover with said body.

14. In a receptacle, the combination with the body thereof, of a rigid frame to give a bevel to the edge of said body, said frame comprising an inner body-portion adapted to be arranged upon the inner face-portions of said body at the upper marginal edge-portions thereof, said inner body-portion being formed upon its upper marginal edge-portion with a curved outwardly and downwardly extending connecting member, and an outer member extending downwardly from said connecting member, said outer member being of less depth than the depth of said inner body-portion and forming with said inner body-portion a receiving part in which

- the upper portions of the body are arranged, said outer and downwardly extending member being provided at pre-determined points with open parts, an off-set forming a seat extending outwardly from said outer and downwardly extending member and located upon the outer face-portions of said body, and a clamping edge-portion extending inwardly from said off-set in biting engagement with the said outer face-portions of said body, combined with a cover, a channel-shaped frame arranged over the marginal edge-portions of said cover, and a means of pivotal connection between said channel-shaped frame and the frame of said body, said channel-shaped frame of the cover registering with the frame of said body and cooperating with said seat to provide a perfect closure of said cover with said body.

15. In a receptacle, the combination with the body thereof, of a rigid body-frame comprising a pair of frame-sections, one of said frame-sections consisting of a pair of vertically disposed portions and an upper connecting member adapted to be arranged upon the upper marginal edge-portions of the front and end-members of said body, and an off-set extending outwardly from one of said vertically disposed portions and located upon the outer face-portions of the front and end-members of said body, said second frame-section consisting of a pair of vertically disposed portions and an upper connecting member adapted to be arranged upon the upper marginal edge-portion of the back member of said body, and a plurality of pintle-receiving members extending from one of the marginal edge-portions of the outer vertically disposed portion of said second-mentioned frame-section, combined with a cover, a channel-shaped frame arranged over the marginal edge-portions of said cover, a strip of metal secured to said channel-shaped frame, a plurality of pintle-receiving members extending from the marginal edge-portion of said strip adapted to be brought into registration with the pintle-receiving members of said second-mentioned frame-section of the body frame, and a pintle-rod in said registering pintle-receiving members, substantially as and for the purposes set forth.

16. In a receptacle, the combination with the body thereof, of a rigid body-frame comprising a pair of frame-sections, one of said frame-sections consisting of a pair of vertically disposed portions and an upper connecting member adapted to be arranged upon the upper marginal edge-portions of the front and end-members of said body, and an off-set extending outwardly from one of said vertically disposed portions and located upon the outer face-portions of the front and end-members of said body, and a clamping edge-portion extending inwardly from said off-set in biting engagement with the said outer face-portions of said front and end-members of said body, said second frame-section consisting of a pair of vertically disposed portions and an upper connecting member adapted to be arranged upon the upper marginal edge-portion of the back member of said body, and a plurality of pintle-receiving members extending from one of the marginal edge-portions of the outer vertically disposed portion of said second-mentioned frame-section, combined with a cover, a channel-shaped frame arranged over the marginal edge-portions of said cover, a strip of metal secured to said channel-shaped frame, a plurality of pintle-receiving members extending from the marginal edge-portion of said strip adapted to be brought into registration with the pintle-receiving members of said second-mentioned frame-section of the body frame, and a pintle-rod in said registering pintle-receiving members, substantially as and for the purposes set forth.

In testimony, that I claim the invention set forth above I have hereunto set my hand this 7th day of March, 1913.

HUGO TUECKMANTEL.
